CALIBRATED VENTILATOR ADJUSTMENT FOR INCUBATORS

Filed June 28, 1927

UNITED STATES PATENT OFFICE

BENJAMIN F. C. MORRIS, OF OKLAHOMA CITY, OKLAHOMA

CALIBRATED VENTILATOR ADJUSTMENT FOR INCUBATORS

Application filed June 28, 1927. Serial No. 202,041.

This invention relates to incubators and like devices, and more especially to a novel ventilating means therefor.

The object of the invention is to provide a novel ventilating means for admitting exactly the proper volume of air to the incubator for ventilating the same during the incubation stages and assisting in maintaining the proper temperature within the incubator, as well as to provide novel accurate, calibrated or micrometer screw adjustment means for such ventilator. While the invention is illustrated in the form of a slide, it is to be understood that the novelty and scope of the invention embodies the same principles irrespective of the manner of adjustment of the sliding device controlling the ventilation. The invention further contemplates a novel ventilation means for the bottom of the incubator which I have found by extensive practical experience serves in the best way to properly ventilate the incubator and which in conjunction with the adjustable ventilating device serves to give a scale or means of determining a dependable and accurate adjustment through the floor of the incubator, which adjustment can be minutely adjusted or regulated as conditions may dictate.

Other and further objects of the invention will be apparent as the description proceeds.

In the accompanying drawings:

Figure 1 is a perspective view of an incubator having a novel ventilating means and adjustment in accordance with the invention.

Figure 2 is an enlarged horizontal sectional view taken on the line 2—2 of Figure 1 and looking in the direction indicated by the arrows.

Figure 3 is an enlarged fragmentary sectional view taken on the line 3—3 of Figure 2 and looking in the direction indicated by the arrows.

Figure 4 is an enlarged fragmentary detailed sectional view showing the connection between a slide block and the adjusting screw.

Figure 5 is an enlarged view of the knurled head of the adjusting screw and the

dial employed in connection therewith for accurately regulating the adjustment of the ventilation.

Figure 6 is a fragmentary sectional elevation taken on the line 6—6 of Figure 3, and

Figure 7 is a detailed perspective view of the adjustment block.

Referring to the drawings, the numeral 8 designates an incubator of any well known or preferred design but particularly one having the supporting legs 9 on which the incubator proper is arranged, provided with the double walls 10 which may have an insulation fibre or asbestos or other filling 11 therebetween, to which the legs 9 are secured. The heater is indicated at 12, having a hood 13 and an automatic control 14 for heating the incubator by circulating hot water, dry hot air or otherwise, suitable heating means extending into and communicating with the interior or incubation chamber from the hood over the burner or lamp heater 12 which sets on the burner base and fuel supply reservoir 15, which may extend beneath the incubator as indicated at 16.

One or more sides of the incubator are provided with a hinged door 17 adapted to swing downwardly on the hinges 18 and held closed by a catch 19 engaging the upper section, while the intermediate section 20 may also hinge downwardly on the lower fixed section 21. The section 21 is adapted to carry a dial plate or dial 23 of suitable shape as shown secured in position by screws or other fastening means 24 having an arrow 25 indicating the normal position from which regulation or turning is gauged.

The bottom of the incubator or floor thereof, is designated at 26 and the sides 27 are preferably provided with an extension 28 at the juncture of the floor which are provided with tenons 29 which are received in grooves or mortises 30 of an adjustable or movable bottom or slide 31. The slide is shorter or of less length than the width of the bottom so as to allow a space 32 in which it may move and is provided with a series of openings of circular or other cross-section as indicated at 33 corresponding

with similar openings 34 in the bottom wall 26 and is adapted to be moved into and out of register therewith to any desired minute degree or entirely, according to the quantity 5 or volume of air adapted to be permitted to enter the interior or incubation chamber of the incubator in a manner to be more fully described. The movable ventilating section or slide member 31 is provided with 10 a bottom strip 35 extending across the same and entering a groove 36 in the bottom or floor 26 to permit free sliding without undue friction and to accurately guide the movable section or slide so that the openings 33 will at all times be maintained in 15 alignment in rows, with respect to the corresponding rows of openings in the floor 26. It also has one end recessed as indicated at 37 and this end receives a block 38 having 20 a threaded horizontal opening 39 therethrough of graduated double or minute pitch of micrometer effect, to give a prescribed movement of the slide for each partial turn of the adjusting screw 40 therein 25 when engaged therewith. The screw 40 also extends through the upturned end 41 of the strip 35 which is bent up at right angles against the end of the block 38 as clearly shown in Figures 4 and 6 in the drawings 30 and is secured therein by screws or the like 42 entering threaded openings 43 in the end of the metal or other block material. The opposite end of the block is provided with a flat extension 44 having threaded openings 35 45 through which fastening screws or the like are inserted for securing the block to the strip or guide member 35, although the openings 45 may be left unthreaded and rivets or other suitable fastening means 46 50 permanently or detachably secured in position therein if desired.

It will be seen that the screw 40 engages the threads of the block aperture 39 and the upturned end 41 threaded or unthreaded, 45 the screw passing through the wall of the incubator at the stationary section 21, as indicated at 47 with suitable guiding means at the inside and being unthreaded at this portion if preferred while also having a 50 flange or annular enlargement or collar 48 to prevent shifting of the screw in its bearing. A knurled head 49 is secured on the outer end of the screw as indicated at 50 and is provided with a series of numbers, 55 preferably from 1 to 6 equally spaced apart, as indicated at 51 to constitute a micrometer dial adjustment in connection with the arrow 25. The pitch of the screw is such that turning the screw through the medium 60 of the knurled head 49 will secure a known adjustment of the movable member or slide 31 which adjustment may be made to effect a complete closing or opening of the openings 33 with respect to the ventilating openings 34 in the bottom of the floor of the in-

cubator cabinet for each complete revolution of the dial, reversely. Thus, the calibrations on the knurled head combined with the arrow 25 will serve to insure positive and accurate adjustment of the ventilator 70 openings with respect to each other so that by determination, the calibrations or figures on the dial can be set to give a predetermined atmospheric condition within the incubator, assuming that the burner is set to furnish a 75 predetermined degree of heat, it being important to have the room well ventilated. Obviously, the atmospheric condition to be obtained may be indicated on the dial or knurled head in lieu of numbers 1 to 6 as 80 shown, so that the atmospheric condition for each adjustment may be seen at a glance instead of referring to a table to indicate the atmospheric condition resulting from the 85 ventilation for each number indicated on the dial or knurled operating head. This of course, is controlled by the volume of air permitted to enter through the openings 33 and 34 when partially or entirely in alignment or registry. Obviously, the incubation 90 is best carried out by maintaining the temperature at a uniform degree, usually 98 at the bottom, 100 at the center and 103 degrees at the top. It may also be pointed out that the sliding connection between the movable member or slide regulator 31 and the bottom floor of the incubator is such as to maintain the slide in positive contact with the floor so that the possibility of air entering the bottom when the openings are out of 95 registry is reduced to nil.

While I have described my invention in a particular form which I have found to be best suited for the purpose, it is to be understood that various changes in the arrangement and proportions of the parts may be made without departing from the spirit and scope of the invention and that in addition to the screw adjustment, preferably a double pitch screw, any other suitable adjustment 100 means may be employed so long as the calibrated dial is set and regulated to give a prescribed atmospheric condition for each adjustment, so that the adjustment and regulation of the ventilation is effected to the 105 minutest and most accurate degree. The result produced is better and a much higher percentage of hatchings in proportion to the 110 number of eggs which are incubated and a positive maintenance of the required atmospheric condition in the incubator and a temperature of 103 degrees such as would 115 be produced by the hen when hatching.

Having thus described my invention, what I claim is:

1. In a ventilating adjustment for incubators, the combination with the floor of the incubator having a series of spaced openings therein adapted to admit unheated atmospheric air through the incubator chamber, 120

a movable slide mounted on the floor and of less width than the floor in the incubator chamber, said slide having openings therein adapted to be moved into and out of 5 register with the openings in the floor, said slide having a recess, a block in the recess having a threaded opening, a bottom strip connected to the slide and to the block and operating in a groove across the bottom 10 in its top surface, a screw having a bearing in the front wall of the incubator and held against movement therein, said screw being threaded into the block and having a head externally of said wall with calibrations 15 thereon, and a pointer on said wall cooperating with said calibrations.

2. In a ventilating adjustment for incubators, the combination with the floor of the incubator having a series of spaced openings 20 therein adapted to admit unheated atmospheric air through the incubator chamber, a movable slide mounted on the floor and of less width than the floor in the incubator chamber, said slide having openings therein 25 adapted to be moved into and out of register with the openings in the floor, a block on the slide having a threaded opening, a bottom strip connected to the slide and to the block and operating in a groove 30 across the bottom in its top surface, a screw having a bearing in the front wall of the incubator and held against movement therein, said screw being threaded into the block and having a head externally of said wall 35 with calibrations thereon, and a pointer on said wall cooperating with said calibrations.

In testimony whereof I affix my signature.
BENJAMIN F. C. MORRIS.
